UNITED STATES PATENT OFFICE.

JOHN JOSEPH GHEGAN, OF EAST ORANGE, NEW JERSEY.

FARADIC MEDICAL APPARATUS.

Application filed April 28, 1919. Serial No. 293,082.

To all whom it may concern:

Be it known that I, JOHN JOSEPH GHEGAN, a citizen of the United States, residing in East Orange, Essex County, New Jersey, have made certain new and useful Improvements in Faradic Medical Apparatus, of which the following is a specification.

This invention relates to faradic medical apparatus; that is, apparatus designed for use in the application of electricity to cure or remedy or alleviate bodily ills or diseases.

The object is to provide an apparatus that can be successfully used, cared for, and operated by technically uneducated or unskilled people or patients.

In this apparatus there is almost universally employed so-called electrodes, one form to be held in the hands and another form to be applied to the surface of the body and adapted to be moistened to increase conductivity, but whatever the form or purpose of the electrode employed, means are provided to supply these electrodes with current impulses and for varying the electro-motive forces. It is necessary to be able to start and stop the supply of electricity at the will of the patient. The starting action must be prompt and certain and the stop action must be so arranged as to immediately, at will, discontinue the use of the current.

There is herein described and shown an apparatus including a Ruhmkorff or Page induction coil, employing a spring-supported, vibrating make and break point. The circuit passes through this vibrating make and break point and through the primary coil of the inductorium. Heretofore it has been the practice to include a two-point contact switch, in series, in the primary circuit, and this was designed to be operated by hand; it caused two break points to occur, in series, in the circuit, and a result of this was sometimes a suspension of operation due to dust or dirt accumulating on the hand operated switch while the inexperienced user would tinker with the other or automatic break point and often put it out of working condition. To obviate this difficulty only one break point is employed in the improved apparatus and that is the vibrating point, the use of which in some form is obligatory.

To accomplish this result the hand oper-

ated switch is employed but it is not in circuit; the hand operated switch is mechanical only, and is arranged and adapted to block and then again to release the vibrating contact. The vibrating contact is the only contact in circuit. When the manual switch is in one position it engages mechanically with the vibrating contact and holds it open; when the manual switch is in the opposite position it releases the vibrating contact, but to insure the prompt start and continued operation of the vibrating contact a snap action or accelerated action is imparted to the manual switch. This is like plucking the spring-supported vibrating contact which, when released by snap action suddenly releases the spring-supported contact and this latter contact strikes the circuit-closing point with an impact, due to its weight and velocity, recoils, and so starts and continues its vibrating movement, and this is done without skill or experience on the part of the patient and invariably follows the movement of the manual switch.

The induction coil is adapted to operate in circuit with the ordinary dry battery, but also operates on the alternating current circuit of commercial form, usually 110 volts and sixty cycles, used for lighting and motor purposes in extended areas of distribution.

The movable parts of the apparatus are enclosed in a box having a hinged cover. Carried by this cover there is a spring contact that engages the mechanical circuit breaking switch fixed in position near the wall of the box, adjacent to the vibrating circuit-breaker. When the cover is closed down the circuit is thus automatically opened.

A transformer of small dimensions is part of the apparatus and is adapted to fit into a lamp socket of an alternating current circuit in any sick room, while a cell or more of dry battery of about the same size and area as the transformer may be employed as an alternative source of supply of electric current, and both these sources of supply, the transformer and the dry battery, fit into position and rest inside the box. Within the box also is arranged the flexible connecting cords for electrically connecting the current with the inductorium, and the inductorium with the electrodes used in the application of current to the human body.

The accompanying drawings illustrate the invention:

Figure 1 shows the enclosing case or box wide open; the inductorium, the connecting cord, and the step-down transformer are shown in the box, while other forms of the electrodes to be employed are secured in position in the cover.

Figure 2 shows the step-down transformer connected to a lamp socket, in an alternating current circuit, by flexible cords, and two electrodes connected to two terminals of the inductorium; the mechanical snap action switch is shown in position to suddenly release the vibrating circuit-breaker.

Figure 3 is a cross-section at 3-3, Figure 2, showing details of the snap switch and the contact stop to engage the switch and automatically open circuit when the cover is closed down; and

Figure 4 is a detail view, showing the manual mechanical snap-switch in position to maintain open circuit conditions.

In Figure 1 the box *b* has a cover *c* hinged to box *b* at *d*. In box *b* there is an induction coil *i* of the Ruhmkorff or Page species having a primary coil disposed inside a secondary coil; the terminals of these coils are shown in sockets 1, 2, 3, on the baseboard 9; these sockets 1, 2, 3, receive the terminals *t* of the flexible conducting cord 10; the opposite terminals are shaped and adapted to connect with the various forms of electrodes, like 11, 12; electrodes fit securely in position or are retained, when out of use, inside the box, as by spring clips like 13. There is a flexible conducting cord *f* lying in the box cover; this cord has terminals 14 adapted to connect with the terminals of the primary coil at 15, the opposite terminals of cord *f*, shown at 16, connect with terminals 17 of the step-down transformer *g*. This transformer *g* has a screw plug terminal, and contacts like an incandescent lamp, adapting it to be connected into an electrical supply circuit *h*; this circuit is, or may be, the commercial circuit carrying an alternating current of, say, sixty cycles and 110 volts.

It is extremely desirable in applying electricity to remedial purpose for human ills, to be able to start and stop the applied current promptly and certainly, and to cut off the current, especially when battery of an electro-chemical nature is employed, to establish normal conditions. The induction coil employed is of the general construction patented to Charles Grafton Page, the primary coil is connected in circuit, in series, with a spring-supported armature 20, on a flat spring 21, on a rigid support 22. There is a stop forming a limit of movement for the armature when attracted by magnetism in core *e*, and the spring has a bias due to its resilience which causes it to

engage a back contact or fixed post or support 23; this contact 23, the primary coil, and the source of electric current are in series and circuit is rapidly made and broken at contact 23. To start the operation it is customary to pluck the spring contact 23 with the finger. A two-point switch has been used in series with the automatic circuit breaker, but this second break point in series with the automatic 70 vibrating contact leads to trouble in inexperienced hands. To guard against this trouble there is provided a two-armed, pivoted lever *s*, moving in a plane parallel with the base 9; one arm 25 abuts the armature, and acts to block it, and then to release it; the opposite end of this two-armed pivoted lever 26 has a button 27, adapted to form a hand or finger contact, and below the lever, between the lever and the base is an inclined plane surface 28 fixed in position so that as arm 26 moves into position to bring arm 25 into position to block armature 20 and open circuit at 23, said arm 26 rides up the incline and is retained in set 80 position, but upon the reverse movement a touch of the operator's finger starts arm 26 down the incline 28, said arm moving with accelerated speed so that the effective release of armature 20 is practically identical with the plucking action of the finger employed by experts; the result is approximately like that of the well-known snap-action switch employed to avoid drawing an arc when circuit is broken. It results 90 that the vibrator is started into action quickly and when so started acts continuously and uniformly.

On the hinged cover is a spring contact, shaped as shown at 30. This, when the 105 cover is closed engages the finger-piece 27, on lever *s* and forces arm 25 into engagement with armature 20, thus opening circuit at 23.

What I claim is:

1. In an electric therapeutical apparatus, an induction coil, in combination with a single point vibrating contact, a manually operated switch for blocking or releasing said vibrating contact, and means, independent of the vibrating contact, for accelerating the releasing action of the manually operated switch.

2. In an electric therapeutical apparatus, an induction coil, a reciprocating armature associated therewith, manually operated means, normally out of circuit with said armature, for blocking or releasing it, in combination with automatic means, independent of said armature, for imparting a snap action to said manually operated means after the latter has been initially started into position where it releases the armature.

3. In an electric therapeutical apparatus, an induction coil provided with a spring,

supported armature, a two arm pivoted lever, one arm of which is adapted to either block or release the armature, manually operated means associated with the other arm 5 for positioning said first arm into either blocking or releasing position with reference to the armature, and means, independent of the armature, for accelerating the movement of the manually operated 10 means into a position where it acts to release the armature.

4. In an inductorium the combination with the vibrating circuit-breaker of an auxiliary lever, an inclined surface separate from the circuit breaker and on which 15 said lever moves and means whereby said lever blocks said vibratory contact when moved in one direction and releases said vibratory contact with an accelerated move-

ment in the opposite direction following 20 the initiation of such movement.

5. In an inductorium, a vibratory contact, an auxiliary pivoted controlling lever therefor adapted to block and release the vibration of said contact and means, independent of the vibrating contact, whereby the releasing movement of said lever, when initiated, is automatically accelerated. 25

6. In an apparatus as described the combination of an enclosing box, a hinged cover 30 therefor, an inductorium including a vibratory contact, a two-armed pivoted lever adapted to block and release said contact, and a projection fixed on said cover, arranged to shift the position of said lever 35 when said cover is closed.

JOHN J. GHEGAN.
